(57) **CLAIM**

The ornamental design for a molding for sealing a motor vehicle windshield panel with a cowl panel, as shown and described.

DESCRIPTION

FIG. 1 is a front perspective view of a molding for sealing a motor vehicle windshield panel with a cowl panel, showing our new design; and,

FIG. 2 is a right end view thereof.

The middle portion of the trim molding is broken away in FIGS. 1 to indicate no particular length. The broken lines in FIGS. 2 show a windshield edge and form no part of the claimed design.
